UNITED STATES PATENT OFFICE.

GUSTAVE E. VILLARET, OF LEONIA, NEW JERSEY, ASSIGNOR TO OWEN WALSH MFG. CO., INC., OF NEW YORK, N. Y., A CORPORATION OF NEW YORK.

DESIGN FOR A BRACKET BACK FOR A WALL LIGHTING FIXTURE.

Application filed April 11, 1927. Serial No. 21,541. Term of patent 3½ years.

To all whom it may concern:

Be it known that I, GUSTAVE E. VILLARET, a citizen of the United States, residing at Leonia, Bergen County, New Jersey, have invented a new, original, and ornamental Design for a Bracket Back for a Wall Lighting Fixture, of which the following is a specification, reference being had to the accompanying drawing, forming part thereof.

Figure 1 is an elevational front view of a

bracket back for a wall lighting fixture showing my new design.

Figure 2 is an end view of the bracket back.

I claim as my invention:

The ornamental design for a bracket back for a wall lighting fixture substantially as shown.
